(57) **CLAIM**

The ornamental design for a solar sensor light, as shown and described.

DESCRIPTION

FIG. 1 is a first perspective view of a solar sensor light showing our new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is a front view of the solar sensor light shown in a position of use with environmental subject matter shown in broken line.

The broken lines shown in the drawings depict portions of the solar sensor light that form no part of the claimed design.
